UNITED STATES PATENT OFFICE.

JOHN MCTAMMANY, OF SPENCER, MASSACHUSETTS, ASSIGNOR, BY MESNE ASSIGNMENTS, TO MCTAMMANY BALLOT COMPANY, OF PORTLAND, MAINE, A CORPORATION OF MAINE.

VOTING-MACHINE.

1,065,703.

Specification of Letters Patent. Patented June 24, 1913.

Application filed July 11, 1896. Serial No. 598,863.

To all whom it may concern:

Be it known that I, JOHN MCTAMMANY, of Spencer, in the county of Worcester and State of Massachusetts, have invented certain new and useful Improvements in Voting-Machines, of which the following is a specification.

This invention has relation to voting machines, and has for its objects, first, to provide a simple and efficient machine by means of which all the voters in a precinct or place may cast their votes; second, to provide a machine which can be readily and expeditiously adjusted for voters having a limited suffrage whereby the latter will be allowed to vote for only the candidates or upon only the questions submitted to them; third, to provide the machine with means whereby it can be quickly prepared for any number of political parties; fourth, to equip the machine with provisions for indicating whether or not the machine is in practical operation without destroying the secrecy of the ballot; fifth, to provide the machine with mechanism for positively resetting the push-pieces or actuators after a voter has cast his vote and thereby avoiding the use of springs, and the consequent disadvantages due to the use thereof; sixth, to provide an improved machine of the type employing a tally-sheet, and a plurality of punches, in which the tally-sheet is manually controlled, and is insured against being tampered with by the voter.

To these ends, the invention consists of certain features of construction and relative arrangement of parts, being embodied in the machine illustrated upon the drawing and now to be described, and set forth in the claims hereunto appended.

Reference is to be had to the accompanying drawings, and to the letters and figures marked thereon, forming a part of this specification, the same letters designating the same parts or features, as the case may be, wherever they occur.

Of the drawings:—Figure 1 represents a front elevation of a machine embodying the invention. Fig. 2 represents a rear elevation, with the back-plate or door opened. Fig. 3 represents a section on line 3—3 of Fig. 2. Fig. 4 represents a similar section, the resetting devices being shown in their operative positions. Fig. 5 represents a similar section with one of the punch-carry-

ing frames removed. Fig. 6 represents a section on the line 6—6 of Fig. 2. Fig. 7 represents a section on the line 7—7 of Fig. 2, looking in the direction of the arrow. Fig. 8 represents a detail plan from the top of Fig. 3. Fig. 9 represents a detail elevation illustrating the obstructing means for locking some of the keys or push-pieces against operation. Fig. 10 represents a similar view with the obstructing means in its operative position. Fig. 11 represents still another similar view, showing the obstructing mechanism arranged to lock other push-pieces. Fig. 12 represents a detail perspective view of the obstructing means. Fig. 13 represents a perspective view of one of the punch-carrying frames or sections detached. Figs. 14 and 15 represent in detail the means for locking the head or casting in rotary position upon the standard. Fig. 16 is a detail perspective view of the visual indicator.

Referring to the drawings,—I have shown one embodiment of my invention in which I employ a tally-sheet and a plurality of perforating punches, but it will be understood that my invention is not limited to that particular type of machine but may be embodied in other forms.

a indicates the upper portion of a suitable standard, which is recessed to receive the end of a spindle *a'* which supports the casing of the voting-machine, and between which and said standard suitable anti-friction balls *a''* may be placed, there being a bearing cone on the spindle and a cup in the standard. A lug *a'''* projecting from one side of the upper end of the standard (see Fig. 8) supports a spring-bolt *a''''*, the upper end of which is adapted to enter one of two or more keepers in the flange of the spindle, whereby the voting-machine may be turned from one position to another on said standard.

b represents the casing, having an open back which may be closed by a suitable door or doors *b'*, and having its front provided with a series of depressions adapted to receive glass slides *b''* between which and the bottoms of the depressions are placed the lists of candidates, which voting lists or captions may be printed upon cards *b'''*. To enable these cards to be removed without removing the glass plates, the top of the front wall of the casing is provided with a notch *b''''* (see Figs. 7 and 8), whereby the

finger-nail or a pin or other suitable implement may be utilized to pull the card up from its position behind the glass.

The ribs of the front wall of the casing 5 between the lists are provided with holes for the plurality of push pieces, keys or actuators, substantially as in my Patent No. 550,055, dated November 19, 1895. These push-pieces, keys or actuators c are provided with the heads c' , as in said patent, rotary movement thereof being prevented by means of the flange c^2 extending along one side of the row of heads (see Fig. 3), these push-pieces being adapted to operate 10 punches which will be presently described.

In some States, women are permitted to vote for school officers; and in order that all of the keys or actuators may be locked against operation or obstructed excepting 15 those which belong to such school officers, on the several tickets, I provide a sliding frame consisting of the horizontal bars d , adapted to slide in suitable guides d' and connected by as many vertical locking bars 20 d^2 as there are rows of punches. The stops or that portion of each bar d^2 which is opposite the particular key or actuator which the woman voter may operate, is provided with a notch d^3 . To one of the bars d^2 is 25 connected one end of a link d^4 , the other end of which is connected to a lever d^5 pivoted to the frame. The elections officer, by opening the back of the casing, may operate said lever so as to shift the locking bars from the 30 position shown in Fig. 9, to a position (see Fig. 10) which will slightly overlap the edges of all the heads c' excepting those which are opposite said notches, thus preventing votes being registered for officers 35 for whom women may not be permitted to vote.

It will be observed that the notched bars d^2 are connected to the sliding bars d by suitable screws. By this means, I am enabled 40 to interchange bars d^2 that are differently notched, (see Fig. 11). That is, if a certain class of voters may vote for a certain plurality of offices, new bars b^2 will be secured to the bars d , said substituted bars 45 being notched so as to prevent the operation of push-pieces for any but the offices for which said class of voters may vote.

Each machine is equipped with a plurality of interchangeable bars d^2 which are 50 so notched that any one or more of the actuators may be easily put in condition for the election in any state, town, or city in which there are voters having a limited suffrage, by putting upon the sliding bars d , 55 the proper obstructing bars d^2 .

Secured to the top and bottom walls of the casing are blocks e provided with ways e' to receive between them the upper and lower ends of the frames which carry the 60 punches and other parts hereinafter de-

scribed. To determine the forward position of these frames, suitable stop-plates e^2 are employed as indicated in Fig. 3; and to hold them in proper position, screws e^3 are let in from the top and bottom walls of the 70 casing, one of said screws being shown in Fig. 7 at the upper end and one at the lower end being indicated in dotted lines. By removing the screws e^3 any one or more of the punch sections may be bodily removed, 75 (see Fig. 13). Therefore, when a machine has been constructed with a sufficient number of such frames or sections for a considerable number of party tickets, then when fewer party tickets are in the field, the 80 extra sections may be removed, thus rendering it absolutely impossible for the voter to manipulate useless keys or push-pieces and improperly perforate the tally-sheet.

The construction of one of the frames for 85 the voting, or vote tabulating mechanism will now be described, it being understood that said frames are duplicates of each other.

A casting f is formed with a front web f' 90 and a rear web f^2 , the front web being drilled to receive the enlarged portion or collars g' of the punches g . To limit the forward movement of the punches, a plate f^3 is secured to the front of the web f' , 95 said plate f^3 being drilled or otherwise provided with openings through which the front spindles of the punches project to be operated upon by the heads c' of the casing. A rear plate f^4 which forms the punch-plate, 100 being provided with suitable holes, is secured to the casting f at a slight distance therefrom, to permit the passage of the tally-sheet h .

In the space between the front and rear 105 webs f' f^2 is a plate f^5 , which may be termed a resetter, setting plate, or member, inasmuch as it is perforated to fit over the punches and to abut against the collars g' to restore them to the position shown in 110 Fig. 5, after some or all have been operated. This setting-plate or member is loosely supported on the punches, so that it may be forced backward by any one or more of the punches which have been operated. To operate this resetting-plate, I employ a rock-shaft f^6 mounted in suitable lugs carried by the casting f and provided with arms f^7 which engage the rear of the setting plate, the lower end of which rock-shaft is provided with an arm f^8 at its lower end. Fitted to slide in a plane intersecting the median lines of the push pieces or actuators 120 is a slide i provided with pins i' , one for each arm f^8 and adapted to engage said 125 arm, as indicated in Fig. 5. One end of said slide i is provided with two pins, or is otherwise loosely connected with the end of an arm j' of a lever j , which is pivoted at j^2 on the spindle of the winding-on roll here- 130

inafter described. This lever *j* is provided with a handle *j*³ and with a spring *j*⁴ adapted to hold it in or restore it to the position indicated in Fig. 4, so as to normally hold the slide *i*, in the position shown in said figure.

As will be readily understood, if one or more of the push-pieces, actuators or keys has been operated, it will push a setting 10 plate *j*⁵ backward and oscillate the rock-shaft to the position indicated in the next to the right-hand frame in Fig. 3. If, now, the lever *j* be operated, the slide *i* will be moved to the left and cause the proper pin 15 *i*⁶ to operate the rock-shaft to restore or set the key or keys.

The supply-roll *h*¹ for the tally-sheet or vote receiver has its upper spindle fitted to a suitable socket *h*², while its lower spindle 20 is fitted to a socket *h*³ having an elongated arm on one side, as indicated in Fig. 3, while a movable block *h*⁴ (see Fig. 2) is adapted to close the opening in the socket *h*³ and rest against the said elongated arm. The 25 winding-on roll *h*⁵ which is provided with a suitable hook *h*⁶ to engage the end of the tally-sheet, has its lower spindle provided with a ratchet *h*⁷ adapted to be engaged by a pawl *h*⁸ pivoted to the lever *j* and held 30 in engagement with the ratchet by means of a spring *h*⁹. A detent-pawl is indicated at *h*¹⁰. This construction permits the winding-on roll being operated by means of the lever *j* after a voter has operated the keys 35 and the arm *j*¹ of the lever simultaneously operates the slide *i*, so as to insure the setting of all the keys whenever the elections officer operates the lever *j* to move the tally-sheet.

40 The movement of the tally-sheet is in a horizontal plane while each row of punches across the machine for the party offices voted for is slightly inclined from the horizontal (see Fig. 2) thus rendering it impossible that one punch shall pass through a hole made by a preceding punch, regardless 45 of the distance that the said tally-sheet is moved. For further illustration and description of this feature, reference may be had to my Patent No. 580,140, granted April 50 6, 1897.

A spindle *l*, represented in Figs. 1 and 16, is connected with the spindle of the winding-on roll and is provided with arms *l*¹ 55 provided with strips *l*² of fabric or with other suitable means to attract the eye to indicate whenever the winding-on roll is operated.

The operation of the push-pieces or actuators is similar to that described in my 60 above-mentioned patent, the differences that exist in the operation having been above pointed out in the description of the details of construction of the present invention. It 65 may be mentioned herein, however, that in

the use of this machine, whenever the voter has indicated his wishes by the operation of certain keys and has operated the punches to perforate the tally-sheet, the elections officer then opens the back of the machine and 70 operates the lever *j*, as above described, to move the tally-sheet and return or set the keys.

The punches are arranged in inclined 75 rows as shown in my former patent above-mentioned, their arrangement being such that each punch perforates the sheet only in a horizontal section of the sheet intended for that punch alone, so that the perforation made by any punch cannot interfere with 80 the perforation made by any other punch.

The arrangement of the casing upon the standard in such way that it may be rotated thereon and then locked in any desirable position is peculiarly advantageous in 85 many respects. Ordinarily, the standards are rigidly secured to the floor, and consequently, when the casing is not rotatable, the push-buttons and the ballots are soon in shadow, as the light changes from morning 90 until night, whereas by rotatably mounting the casing, the latter may be swung into position to receive the daylight from the windows during the day, and the light at night from the artificial lighting means. 95

One of the most important features of the present invention is the mechanism by means of which the push-pieces are positively reset after they have been manipulated by a voter. Heretofore, it has been the practice to reset 100 or return to normal position the push-pieces by means of springs, and consequently much trouble has been experienced by reason of the breakage or snapping of said springs, and the delay incident to substituting new 105 ones. This trouble has been augmented by the fact that the replacing of the springs has in many cases caused the opening of the machine in such way as to destroy the secrecy of the ballot. 110

It is desirable that the push-pieces should move easily under pressure in order that voters of all degrees of strength and intelligence may move them sufficiently to cause the tabulating of the vote, and hence a heavy 115 or strong resetting spring cannot be used, and where light springs are employed the push-pieces constantly stick and are not returned to normal independent position. Thus it will be seen that by the employment 120 of means for positively (in contradistinction to yieldingly, as through the medium of a spring) resetting the push pieces, I have obviated the use of the springs, have simplified the construction of the machine, and 125 have provided against the machine getting out of order during the election. Moreover, by employing the positive resetting means, the push-pieces meet with no resistance, except that caused by the vote tabulating 130

means and the push pieces are always moved their full extent to cause the tabulating of the vote.

I do not herein claim broadly mechanism for obstructing any of the actuators or voting mechanisms, this being set forth and claimed in my co-pending application, Serial No. 692,068, filed Feb. 28, 1898.

Having thus explained the nature of the invention, and described a way of constructing and using the same, though without having attempted to set forth all of the forms in which it may be made, or all of the modes of its use, I declare that what I claim is:—

1. The combination of a tubular standard *a* having a ball-cup, a voting machine casing having a reduced spindle *a'* provided with a bearing-cone and projecting into the upper end of the said standard, anti-friction balls inserted between said cup and said cone, and a spring bolt *a''* carried by the said standard and adapted to enter one of a plurality of recesses or keepers in a portion of said spindle.

2. A voting machine comprising in its construction, a tally-sheet and a roll therefor, and a spindle connected with said roll and extending outside the casing and provided with arms carrying flexible material at their ends, for indicating to the eye that the roll is operated, said arms being located at a sufficient distance from the casing of the machine to permit of the waving of said flexible material.

3. A voting machine comprising a casing having provisions for receiving and supporting a plurality of vertical voting lists or captions, a plurality of vertical rows of actuators alternating with the voting lists or captions, vote-tabulating mechanism operated by the actuators, a separate independently supported positive resetting device for each row of actuators, and means for positively actuating said devices simultaneously.

4. A voting machine comprising a casing having provisions for receiving and supporting a plurality of vertical voting lists or captions, a plurality of vertical rows of actuators, alternating with the voting lists, vote-tabulating mechanism operated by the actuators, a separate positive resetting device for each row of actuators, and a movable member having provisions for positively actuating said resetting devices simultaneously.

5. A voting machine comprising a casing having provisions for receiving and supporting a plurality of vertical voting lists arranged in parallelism, a plurality of vertical rows of actuators alternating with said voting lists, a resetter behind each row of actuators for positively resetting all the actuators in the row, a movable member, and

a plurality of operative connections between said member and said resetters, whereby said actuators are positively reset simultaneously.

6. A voting machine comprising a casing having provisions for receiving and supporting a plurality of vertical voting lists or captions, a plurality of vertical rows of actuators alternating with said voting lists, a plurality of interchangeable removable sections each containing vote-tabulating mechanism, and each section being complementary to a row of actuators, a positive resetter in each section for all the actuators for the vote-tabulating mechanism therein, and means for actuating all of said resetters, said resetters being detachable from said means, whereby the sections and the resetters therein may be placed operatively in or removed from the casing.

7. A voting machine comprising a casing having provisions for receiving and supporting a plurality of elongated vertical voting lists or captions, a plurality of actuators arranged in vertical rows alternating with said voting lists, resetting devices for positively resetting all of said actuators, and means independent of said resetting devices and of any voting mechanism for obstructing and thereby rendering inoperative certain actuators whereby the machine is adapted for the vote of a restricted voter.

8. In a voting machine, the combination with the rolls *h'* and *h''* for the tally-sheet, a series of shouldered punches for perforating the tally-sheet, a setting plate for the punches said plate having apertures for said punches and loosely supported by the stems thereof, the ratchet *h'* connected with the roll *h''*, and the lever *j* having a pawl *h''* 100 engaging said ratchet and having connections with the punch-setting plate.

9. A voting machine comprising a vote receiver, a plurality of actuators, means for positively resetting said actuators comprising a plate having the plane of its face intersecting the paths of movement of said actuators, said plate being movable in the direction of movement of the actuators, and a rock shaft having means for moving said 110 plate.

10. A voting machine comprising in its construction a series of punches adapted to perforate a tally-sheet, manually operated actuators or keys independent of said 120 punches for operating them, said actuators or keys being located in the front of the machine and accessible to the voter, and means for resetting said punches and keys or returning them to normal position, said means being inaccessible to the voter, and including a plate loosely mounted upon and supported by the stems of the punches and a device for moving said plate toward operative position.

11. In a voting machine, the combination with the manually operable punches provided with collars g' and having operating means arranged in the front of the machine 5 accessible to the voter, of the plate f^5 adapted to slide relatively to the actuators, the rock-shaft f^6 provided with arms f^7 adapted to engage said setting-plate, and with the arm f^8 and means for operating 10 said rock-shaft.
12. In a voting machine, the combination with actuators, of the plate f^5 adapted to move relatively to said actuators to set them, the rock-shaft f^6 provided with arms f^7 adapted to engage said setting-plate and with the arm f^8 , the slide i provided with means for engaging the arm f^8 , and the lever j provided with an arm j' , connected with said slide. 15
13. A voting machine comprising a casing, and a plurality of interchangeable independent frames adapted to be secured to or removed from said casing without changing or disturbing each other, said frames being provided with complete voter-controlled 20 devices for tabulating votes and a vote receiver common to the tabulating devices of all said frames.
14. A voting machine comprising a casing, and a series of frames adapted to be secured to or removed from said casing, each of said frames being provided with a plurality of actuators, and with means for positively resetting said actuators. 25
15. A voting machine comprising a casing, a series of interchangeable independent frames detachably supported on said casing, and removable independently of each other, voter controlled devices supported on each 30 frame for tabulating votes, the devices on one frame being detached from and independent of those on another frame, and a vote receiver common to the tabulating devices of all of said frames. 35
16. A voting machine comprising in its construction a series of guides or blocks, and a series of frames adapted to be secured to or removed from said blocks or guides, each of said frames carrying a plurality of 40 punches, a perforated punch-plate, a space being provided between the punches and the punch-plate for the passage of a tally-sheet, and a positive resetter for the punches. 45
17. A voting machine comprising in its construction a series of guides or blocks, and a series of frames adapted to be secured to or removed from the said blocks or guides, each of said frames carrying a plurality of actuators, a plate for setting the 50 actuators in normal position, and a rock-shaft for operating said plate. 55
18. A voting machine comprising in its construction, a plurality of blocks or guides, a plurality of detachable frames secured to 60 said guides, a plurality of vote-tabulating devices carried by each frame, a separate resetting device for the vote-tabulating devices in each frame, and means for operating all of said resetting devices simultaneously. 65
19. A voting machine comprising a casing having provisions for receiving and supporting a plurality of voting lists or captions, a plurality of rows of actuators alternating with said voting lists and supported by said casing, a plurality of interchangeable detachable frames one for each row of actuators and each frame carrying vote-tabulating mechanism equal in number to the actuators in the row, and detachable means for positively resetting all of said 70 actuators. 75
20. A voting machine comprising in its construction a series of rows of actuators, and a sliding frame including a series of notched bars, one bar for each row of actuators, the said bars being adapted to obstruct the operation of some of the actuators in each row, while the notches leave other actuators free to be operated. 80
21. In a voting machine, the combination with the punches, of the actuators c provided with heads c' , and the sliding notched locking-bars d^2 adapted to move to and from a position to obstruct the operation of some of the actuators. 85
22. A voting machine comprising a supporting frame and a series of sections detachably secured thereto, each section representing a given party or a number of candidates of the same political complexion, 90 each section comprising a frame, a plurality of actuators, a plurality of voting mechanisms mounted therein and a resetter for positively resetting the actuators, the detachability of the sections enabling the number of sections to be varied according to the 95 number of parties or candidates in the field. 100
23. In a voting machine, a series of actuators and a series of interchangeable bars arranged and adapted to obstruct certain of said actuators without obstructing others in the same series. 105
24. In a voting machine, a plurality of vertical rows of actuators, and a plurality of vertical bars arranged to move laterally toward and obstruct certain of said actuators without engaging the others of said set or series. 110
25. In a voting machine, a supporting frame having a wall or partition provided with apertures, actuators operating through said apertures, a series of recording devices, means for actuating said recording devices, a receiver for the records made by said devices, and an obstructing device or stop under control of an election officer for preventing the operation of certain of the actuators while others are left free to be operated. 115
26. In a voting machine, a plurality of 120
- 125
- 130

- sections in which are mounted the actuators and the vote-tabulating mechanism, said sections being removable, in combination with an obstructing device having a plurality of detachable or interchangeable stops, one for the actuators in each section.
27. A voting machine comprising in its construction a series of actuators arranged as sections in horizontal rows, and a sliding frame having interchangeable or detachable means for obstructing any one or more of the actuators in any one or more of said rows.
28. A voting machine comprising elongated voting lists, a row of actuators extending alongside each voting list, mechanism for tabulating the votes, and a plurality of positive resetting devices for returning the actuators to normal position.
29. A voting machine comprising elongated voting lists, a row of actuators extending alongside each voting list, mechanism for tabulating the votes, and a plurality of independently mounted devices one for each row of actuators to positively reset the same.
30. A voting machine comprising a plurality of actuators arranged in rows, vote tabulating mechanism operated by said actuators, a device for resetting each row of actuators, and means for operating all of said devices.
31. A voting machine having a vote receiver, a plurality of actuators, a single movable intervening member between each actuator and said vote receiver, and positive resetting devices directly engaging and actuating said members.
32. A voting machine having a plurality of actuators arranged in vertical rows, vote tabulating mechanism in operative relation thereto, a movable member arranged vertically in the rear of each row of said actuators, and means for positively moving said members forward, or horizontally, to positively reset the said actuators simultaneously.
33. In a voting machine, a casing, voting mechanism within the casing, means under the control of an elections-official for permitting and preventing the operation of a predetermined number of the voting mechanisms while leaving the others free to be actuated by the voter, and means for positively resetting the actuated voting mechanism.
34. In a voting machine, a casing, a plurality of independent removable frames each having voting mechanism, an obstructing device for controlling the voting mechanism of all or any one of said frames, and a resetting device for returning the unobstructed voting mechanisms actuated by a voter, both of said devices being under control of an elections-official.
35. In a voting machine, a casing, voting mechanism in said casing, a sliding frame or device in said casing for obstructing certain of the voting mechanisms, and a supplementary frame or device within the casing and supported thereby for positively resetting the unobstructed mechanisms.
36. In a voting machine comprising in its construction, actuators, vote-tabulating mechanism, and a plurality of frames within the casing arranged to obstruct and positively reset the actuators respectively.
37. In a voting machine, a casing, voting mechanism in said casing, and means under control of an elections-official for obstructing one portion and positively resetting another portion of the voting mechanism.
38. In a voting machine, a casing, a plurality of removable frames within the casing, each having voting mechanism and resetting devices for said voting mechanism, a traveling bar arranged and adapted to engage and actuate the aforesaid resetting devices, and a spring-tensioned lever for actuating the traveling bar or frame.
39. In a voting machine, a casing, a plurality of voting lists supported on the front of said casing, a row of actuators alongside each of said voting lists, voting mechanism within the casing and in operative relation to the actuators, a resetting device for each row of actuators and a horizontally movable bar or frame within the casing arranged and adapted to simultaneously engage and operate the resetting devices.
40. In a voting machine, a casing, a plurality of vertical voting lists supported by one side of the casing, each list representing a political party, a plurality of rows of actuators alongside said lists and an independent resetting device for all of the actuators in each row.
41. In a voting machine, a casing, a plurality of vertical voting lists on the front of said casing, a row of actuators alongside of said voting lists, voting mechanisms in operative relation to the actuators, a resetting device for each row of actuators, a traveling bar or frame for operating all of said resetting devices simultaneously and a spring-tensioned lever for actuating said bar.
42. In a voting machine, a casing, a plurality of voting lists, a plurality of independent detachable frames or sections in said casing each having a voting mechanism with an actuator, an independent resetting device for all the actuators of the voting mechanisms of said frames, and a device arranged and adapted to positively and simultaneously actuate the resetting devices for all of said frames.
43. In a voting machine, a casing, a plurality of similar frames or sections detachably supported in said casing, and each having voting mechanism and a positive reset-

ting device for the voting mechanism, and means for securing each section in position in the casing, independently of the other sections.

5 44. A voting machine comprising a plurality of independent sections or frames having a series of actuators, a series of voting mechanisms each adapted to be operated by an actuator and a positive resetter 10 for the actuators, and a casing having provisions for the reception and removal of a variable number of said sections or frames, according to the number of political parties in the field or propositions to be voted on, 15 said casing having a series of rows of apertures in its front, through which the voting mechanisms may be actuated, each row corresponding to one of said independent sections.

45. In a voting machine, a casing, a series 20 of independent frames in said casing, voting mechanism mounted in each of said frames and a device common to all the frames for positively resetting the voting mechanism in each frame, said device permitting the removal or insertion of the frames.

In testimony whereof I have signed my name to this specification in the presence of two subscribing witnesses, this 6th day of 25 July, A. D. 1896.

JOHN McTAMMANY.

Witnesses:

C. F. BROWN,
A. D. HARRISON.
